(57) **CLAIM**

The ornamental design for an absorbent article, as shown and described.

DESCRIPTION

FIG. 1 is a perspective view of an embodiment of an absorbent article showing our new design;

FIG. 2 is a perspective view of an embodiment of an absorbent article showing our new design;

FIG. 3 is a top view of the absorbent article as shown in FIG. 1;

FIG. 4 is a bottom view of the absorbent article as shown in FIG. 1 or 2;

FIG. 5 is a left side view of the absorbent article as shown in FIG. 1 or 2;

FIG. 6 is a right side view of the absorbent article as shown in FIG. 1 or 2;

FIG. 7 is a front side view of the absorbent article as shown in FIG. 1 or 2; and,

FIG. 8 is a back side view of the absorbent article as shown in FIG. 1 or 2.

Any patent application or patent to which this application claims priority or benefit thereof, is hereby incorporated herein by reference in its entirety.

The broken lines shown in the figures illustrate portions of the absorbent article that form no part of the claimed design.

1 Claim, 3 Drawing Sheets

Related U.S. Application Data

division of application No. 29/487,353, filed on Apr. 8, 2014, now Pat. No. Des. 774,187, which is a division of application No. 29/404,135, filed on Oct. 17, 2011, now Pat. No. Des. 705,927.
